THROAT PLATE

Ragnar W. Winberg, Floral Park, N.Y.

Application February 21, 1957, Serial No. 641,579

9 Claims. (Cl. 112—260)

The present invention relates to the manufacture of an improved throat plate for sewing machines, and in particular to a throat plate which is constructed to serve as a circuit completing element in a bobbin runout detection system.

My U.S. Patent No. 2,854,938 of October 7, 1958 is concerned with the problem of providing a visual warning or control function when the supply of bobbin or bottom thread in a sewing machine is about to become exhausted. The purpose of obtaining this warning or control function is to apprise the operator that the bobbin must be replaced or to achieve an automatic shutdown of the machine. As detailed in my U.S. Patent No. 2,854,938 of October 7, 1958, I have found that the electrical conductivity state or condition of the bobbin thread may be changed from its normal state along a section adjacent to and spaced from the innermost end of the wound bobbin. Upon feeding of this section of changed electrical conductivity to or through the sewing mechanisms, the change in electrical conductivity may be sensed and employed to initiate the warning or control function. In an illustrative embodiment according to my previous invention, a bobbin is provided which is of comparatively non-conductive thread and is wound on the conventional bobbin spool or in a coreless form with a section or length of the bobbin thread adjacent to and spaced from its innermost end treated with electrical powder to provide conductive surfaces of low electrical resistivity and high electrical conductivity. During the normal operation of the sewing machine, the wound bobbin delivers thread which is of the usual low conductivity until such times as the section or length of high conductivity is pulled from the bobbin and advanced through the stitching mechanisms. This high conductivity section, which may be made exceptionally short in length, is employed to physically complete an electrical circuit, which circuit stays energized until the sensing or detecting mechanism is reset by the operator. The circuit was completed in accordance with the teachings of my patent by isolating the segment of the throat plate surrounding the needle hole from the remainder of the machine and relying upon the electrically conductive section coming through the needle hole and bridging the isolated segment to a contiguous portion of the machine whereby the circuit was activated for achieving the warning or control function.

It is an object of this invention to provide an improved throat plate for use in a bobbin runout detection system of the aforesaid character. Specifically, it is within the contemplation of the present invention to provide an improved throat plate constructed to allow for the completion of the control circuit for the runout detection system in response to an exceptionally small or short region of electrically conductive material applied to the bobbin thread adjacent its innermost end.

In accordance with an illustrative embodiment demonstrating features of the present invention, the improved throat plate comprises a main body having a needle

2

hole and a channelway extending adjacent and rearwardly of the needle hole. A lead-in wire and contact means lie within the channelway and are bonded therein in insulated relation to the main body of the throat plate with the contact means lying substantially rearwardly of and adjacent to the needle hole. Advantageously, a thread guideway is provided rearwardly of the needle hole and along the line where the stitching normally passes, with the contact means extending along and bounding one side of the thread guideway and with the plate proper extending along and bounding the other side of the thread guideway. The thread guideway is dimensioned so that the electrically conductive region, although exceptionally short in length and comparable in section to the normal cross-section of the thread, will bridge the width of the guideway and complete the electrical connection of the contact means to the plate proper which energizes the associated warning or control circuit.

In accordance with method aspects of the present invention, a conventional throat plate of the type usually employed in a sewing machine may be modified for use as part of my improved bobbin runout detection system by forming a channelway in the throat plate having a section extending adjacent the needle hole, electrically assembling a lead-in or terminal wire and a contact member, placing the assembly of the wire and the contact member in the channelway with the contact member rearwardly of the needle and with the assembly insulated from the throat plate, and bounding the assembly in the channelway so that for all intents and purposes the assembly is an integral part of the throat plate. To advantage, a throat plate constructed substantially in accordance with my method is not structurally weakened and the presence of the isolated contact member and the terminal wire does not interfere with its normal construction which enables its use with the conventional feed dog and presser foot of the sewing machine.

The above brief description, as well as further objects, features and advantages of the present invention will be best appreciated by reference to the following detailed description of a presently preferred, but illustrative embodiment and the details of a typical method of assembly, when taken in conjunction with the accompanying drawings, wherein:

Fig. 1 is a perspective view, partially exploded, showing the component parts of an improved throat plate in accordance with the present invention;

Fig. 2 is a plan view, on an enlarged scale and partially broken away, showing a completed throat plate embodying features of the present invention;

Fig. 3 is a sectional view on an enlarged scale taken substantially along the line 3—3 of Fig. 1 and showing a first step in the assembly of a terminal or lead-in wire with the throat plate in accordance with the present invention;

Fig. 4 is a view similar to Fig. 3 but showing the insulated lead-in or terminal wire as assembled with the throat plate;

Fig. 5 is a view similar to Fig. 4 after the excess material above the top face of the throat plate and a portion of the lead-in wire are removed, said view being taken substantially along the line 5—5 of Fig. 2; and

Fig. 6 is a sectional view taken substantially along the line 6—6 of Fig. 2, a thread being shown in cross section lying within the thread guideway rearwardly of the needle hole.

Referring now specifically to the drawings, there is shown in Fig. 1 the component parts of an improved throat plate 10 in accordance with the present invention which includes a main body or plate part 12, a lead-in wire 14, contact member 16, a terminal plug 18 and a connecting wire 20.

The main body or throat plate proper 12 is essentially of conventional construction and includes a needle hole 22, a number of feed slots 24 and countersunk holes 26. The needle hole 22 permits the needle of the sewing machine to extend through the throat plate 10 for co-action with the hook and bobbin mechanisms; the feed slots 24 permit the work-contacting surfaces of the four-motion feed dog of the machine to engage the under-surface of the work and to advance the same past the needle; and the holes 26 enable the mounting of the throat plate 10 on the sewing machine as part of the feed bed thereof.

In accordance with the present invention, the throat plate is modified to incorporate a channelway 30 or slot which extends rearwardly from the needle hole 22 at a location offset to one side of the needle hole and spaced from and parallel to the line L, along which the stitching or seam moves during normal operation of the sewing machine. As seen best in Figs. 3 to 5, inclusive, the channelway 30 is dovetailed in cross section for a purpose to be subsequently described. At its rearward end, the channelway 30 is in communication with a terminal opening 32 which receives the insulating terminal plug 18 in a manner to be subsequently described. At its forward end the channelway or slot 30 is in communication with a laterally-extending cut out 34 which has one side contiguous with the outer side of the channelway 30 and has its other side extending to and terminating substantially along the stitch line L and at a location in alignment with and rearwardly of the needle hole 22. The disposition of the channelway 30 and the cutout 34 is such as not to interfere with the required slots 24 for the feed dog. However, in some installations, it will be necessary to modify the feed dog by cutting away portions thereof. Despite the necessity for possible modification of the feed dog, the comparatively narrow channelway 30 and the small cutout 34 do not interfere with providing the required clearance for the work-engaging surfaces of the feed dog to come into contact with the under surface of the assembly to be stitched.

The contact member 16 is mounted on the forward terminal portion 14a of the terminal or lead-in wire through the provision of a welded or soldered joint 36 (see Fig. 6). The terminal portion 14a of the wire 14 may extend for substantially along the entire adjacent side of the contact member 16 to assure adequate electrical connection between the wire and the contact member and to provide the requisite mechanically rigid assembly between the wire and the contact member. The contact member 16, which is in the form of an insert or inlay for the throat plate, may be fabricated of any electrically conductive material, but preferably is of the same material as the throat plate proper.

The insulating plug or terminal 18 may be a molded piece of ceramic or may be of plastic. It has been found convenient to employ a plug made of Zytel to surround the rear end portion of the lead-in wire 14 to which rear end portion is electrically joined the connecting wire 20. This connecting wire is connected to an energization coil of a relay or to a microswitch or any other control element of the sensing or control circuit. A typical circuit used in accordance with the present invention is detailed in my said patent.

Reference will now be made to Figs. 2 and 6 for a description of the completed throat plate in accordance with the present invention. As seen in Fig. 2, the contact member 16 disposed in the cutout 34 and the terminal or lead-in wire 14 lies within the channelway or slot 30, the assembly of said channel contact member 16 and the lead-in wire 14 being insulated from the plate proper by the provision of insulating material, generally designated by the reference numeral 38. The terminal plug 18 extends through the terminal opening 32 and serves to insulate the lead-in wire 14 from the plate proper. As seen best in conjunction with Fig. 6, the contact member 16

extends laterally in front of the lead-in wire 14 which is connected at the side of 16a thereof. At its opposite side 16b the contact member 16 terminates substantially along the line to be ultimately occupied by the thread T. Although a single strand of thread is shown in Fig. 6, it will be appreciated that this thread is part of a stitched assembly and diagrammatically represents the bobbin thread which is part of the stitched assembly, the remaining portions of the stitched assembly and the top thread being deleted for the purpose of illustration.

A thread guideway 40 is provided along the stitch line L rearwardly of the needle and is bounded at one side by the adjacent side 16b of the contact member 16 and at the other side by the plate proper. Extending between the needle hole and the adjacent end of the thread guideway 40 is a small chute, designated generally by reference numeral 42, which has a chamfered base extending upwardly from its forward end which is disposed below the top face 12a of the plate 12 and terminates in the guideway. The chute has somewhat convergent side walls 42a, 42b which merge into the adjacent sides of the thread guideway.

Reference will now be made in sequence to Figs. 3 to 5, inclusive, for a detailed description of the present method of modifying a conventional throat plate for use as part of my run-out detection system.

Initially the throat plate 12 is formed with the channelway 30, the terminal opening 32 and the cutout 34 as detailed in conjunction with Fig. 1. Thereupon, a first quantity 38a of a suitable bonding resin is placed in the channelway 30 and the terminal or lead-in wire 14 is wrapped in a partial sheath of insulating paper 44. A second quantity 38b of bonding resin is filled in about the wire and within the partial sheath 44. Thereupon the assembly of the wire 14 and the sheath 44 is placed within the channelway 30 (see Fig. 4) with the wire 14 insulated from the throat plate 12 by the resinous mass 38a, 38b and the paper sheath or separator 44. In a similar fashion the contact member 16 which is slightly undersized in relation to the cutout 34 is placed within the cutout and insulated therefrom by the application therebetween of the bonding resin and a sheath. The terminal plug 18 is either force fitted into the opening 32 or bonded therein by an adhesive. A suitable bonding resin which has been found to be particularly useful in accordance with the present invention is an epoxy resin in liquid form which is cured with an appropriate epoxy hardener. Such epoxy resins are available in the market under the Bakelite trademark and are identified as epoxy resin ERL-2795 and epoxy hardener ERL-2807. Suitable formulations are four to five parts of the epoxy resin to one part of the epoxy hardener. Once the epoxy resin is cured, the same provides an integral bond which fixes the wire 14 and the contact member 16 in the channelway and cutout. The dovetail construction of the channelway 30, as seen in Figs. 3 to 5, inclusive, assures that the hardened resinous insert cannot readily pull out from its confining slot. After the assembly illustrated in Fig. 4 has hardened, the uppermost face 12a of the throat plate 12 is sanded, for example by placing the same face down on a sanding belt, to remove the excess hardened resin above the level of the face 12a. Incident to such removal, portions of the sheath or paper separator 44 are sanded away; and as illustrated in Fig. 5, any portions of the wire 14 which project above the plane of the face 12a is chamfered off. When completed the wire 14 is adequately insulated from the throat plate 12 by the paper separator 44 and the hardened resinous mass 38. As seen in Fig. 6, a similar paper wrap or separator 46 is employed in conjunction with the inlay or insert 16 to assure that the same will be electrically isolated from the bounding walls of the cutout 34. In some instances it may be advantageous to make the cutout 34 of inverted dovetail section so that if any downward force is exerted on the inlay during normal use, said force will

not dislodge such contact from the cutout 34. In some instances it may not be necessary to employ the paper separators or sheaths 44, 45 in effecting the assembly; however, such sheaths are particularly useful due to the comparatively small clearances between the wire and the contact member and the surrounding portions of the plate.

After the wire and the contact member are embedded within the plate, the guideway 40 is completed by milling a slot and as a part of this operation the guiding funnel 42 is formed intermediate the needle hole 22 and the thread guideway 40.

The conventional sewing machine is modified to employ the present throat plate in conjunction with bobbin run-out detecting system of the type described in detail in my said patent. Such modification involves the attachment to the sewing machine of a sensing unit which is electrically connected to the wire 20, the use of the specially prepared bobbin with the electrically conductive section, and the replacement of the standard throat plate with the present improved throat plate. As the conductive portion of the thread comes up through the needle hole 22 during normal operation of the stitching mechanisms of the machine, such conductive portion is directed to the thread guideway 40 by the funneling channel 42. Upon entering such thread guideway the conductive portion effectively bridges the contact member 16 to the throat plate proper. This is effective in the control circuit to initiate the desired external function incident to the detection of runout of the bobbin thread. It will be appreciated that by proper dimensioning of the thread guideway 40, that is by having a guideway substantially of the width of the thread, a small electrically conductive portion on the thread will be sufficient to at least momentarily bridge the contact member 16 to the throat plate proper to connect these two electrical terminals together.

Experience indicates that the present improved throat plate is virtually as strong as the conventional throat plate and the presence of the insulated contact member 16 and lead-in wire 14 do not structurally weaken the throat plate or interfere with the operation of the feed dog or the needle of the sewing machine.

A latitude of modification, change and substitution is intended in the foregoing apparatus and method and accordingly the claims should be interpreted broadly and in a manner consistent with the spirit and scope of the disclosure. In some instances, some features of the invention will be used without a corresponding use of other features.

What I claim is:

1. An improved throat plate for a sewing machine comprising a main body of electrically conductive material having a needle hole and a channelway extending adjacent said needle hole, a lead-in wire and contact means both of electrically conductive material lying within said channelway, and means in said channelway bonding said wire and contact means to said main body and insulating said wire and contact means from said main body.

2. An improved throat plate for a sewing machine comprising an electrically conductive main body having a needle hole and a cutout extending adjacent said needle hole, electrically conductive contact means lying within said cutout, and means in said cutout bonding said contact means to said main body with said contact means insulated from said main body.

3. An improved throat plate for a sewing machine comprising an electrically conductive main body having a needle hole and a cutout extending adjacent said needle hole, a lead-in wire having an electrically conductive contact part lying within said cutout, and means bonding said wire and contact part to said main body and insulating said wire and contact part from said main body.

4. An improved throat plate for use with a bobbin

runout detection device comprising a main plate having a needle hole, said main plate being formed with a slot extending rearwardly from said needle hole at a location spaced from and substantially parallel to a stitch line extending rearwardly of said needle hole and in alignment therewith, said main plate being formed with a cutout, said slot opening laterally at the end thereof adjacent said needle hole into one side of said cutout, said cutout terminating at the other side thereof substantially along said stitch line, a lead-in wire disposed in said slot, means mounting said wire in said slot in insulated relation from said main plate, a contact member disposed in said cutout and electrically connected to said wire, and means mounting said contact member in insulated relation from said main plate with said contact member having a side extending substantially along said stitch line.

5. An improved throat plate for use with a bobbin runout detection device comprising a main plate having a needle hole, said main plate being formed with a slot 10 extending rearwardly from said needle hole and at a location laterally spaced from a stitch line extending rearwardly of said needle hole and in alignment therewith, said main plate being formed with a cutout, said slot 15 opening laterally at the end thereof adjacent said needle hole in said cutout, said cutout terminating substantially along said stitch line, a lead-in wire disposed in said slot, means mounting said wire in said slot in insulated relation from said main plate, a contact member disposed in said cutout and electrically connected to said wire, means mounting said contact member in insulated relation from said main plate with said contact member having a side extending substantially along said stitch line, said main plate being formed with a thread guideway along said stitch line and having at one side thereof said contact member.

6. An improved throat plate for use with a bobbin runout detection device comprising an electrically conductive main plate having a needle hole disposed along a stitch line extending rearwardly of said needle hole and 20 in alignment therewith, said main plate being formed with a cutout at one side of said stitch line and terminating at one of its sides substantially along said stitch line, an electrically conductive contact member disposed in said cutout, and means mounting said contact member in insulated relation from said main plate with one side of said contact member extending substantially along said stitch line.

7. An improved throat plate for use with a bobbin runout detection device comprising an electrically conductive main plate having a needle hole disposed along a stitch line extending rearwardly of said needle hole and in alignment therewith, said main plate being formed with a cutout at one side of said stitch line and terminating at one of its sides substantially along said stitch line, an electrically conductive contact member disposed in 45 said cutout, means mounting said contact member in insulated relation from said main plate with said contact member extending substantially along said stitch line, said main plate being formed with thread-guiding means extending along said stitch line and having said contact member bounding one side of said thread guiding means.

8. An improved throat plate for use with a bobbin runout detection device comprising an electrically conductive main plate having a needle hole disposed along a stitch path which extends rearwardly of said needle hole, said main plate being formed with a cutout at one side of said stitch path, said cutout terminating at a bounding edge extending substantially along said stitch path, an electrically conductive contact member disposed in said cutout, and insulating means mounting said contact member in insulated relation from said main plate, said contact member having one of its edges extending substantially along said stitch path, said one edge of said contact member being substantially coextensive with said bounding edge of said cutout and being separated there-

from by said insulating means whereby an electrical path may be completed between said main plate and said contact member when the coextensive edges are bridged by a conductive material.

9. An improved throat plate for use with a bobbin runout detection device comprising an electrically conductive main plate having a needle hole disposed along a stitch path which extends rearwardly of said needle hole, said main plate being formed with a cutout at one side of said stitch path, said cutout terminating at a bounding edge extending substantially along said stitch path, an electrically conductive contact member disposed in said cutout, and insulating means mounting said contact member in insulated relation from said main plate, said contact member having one of its edges extending 10

substantially along said stitch path, said one edge of said contact member being substantially coextensive with said bounding edge of said cutout and being separated therefrom by said insulating means whereby an electrical path

5 may be completed between said main plate and said contact member when the coextensive edges are bridged by a conductive material, and thread guiding means formed along said stitch path rearwardly of said needle hole.
